UNITED STATES PATENT OFFICE.

MARTIN LEWIS JANES, OF NEW YORK, N. Y.

COMBINED BLOOD-TRANSFUSION AND ASPIRATING APPARATUS.

1,346,127.

Specification of Letters Patent. Patented July 13, 1920.

Application filed March 20, 1920. Serial No. 367,357.

To all whom it may concern:

Be it known that I, MARTIN L. JANES, a citizen of the United States, and resident of the borough of Bronx, county of Bronx, and city and State of New York, have invented certain new and useful Improvements in Combined Blood-Transfusion and Aspirating Apparatus, of which the following is a specification.

10 This invention relates to improvements in blood transfusing apparatus.

The invention has for one of its objects the provision of a multiple cylinder pumping apparatus so constructed as to provide a continuous flow of blood from the donor to the receiving patient and prevent accidental back-flow of the blood.

Another object of the invention is to provide means for supporting and operating 20 opposed pumping devices adjustable to cooperate with pumps of different lengths and to vary the length of stroke of the pump pistons.

A further object of the invention is to 25 provide a multiple cylinder pumping apparatus, and means for supporting the pump cylinders and actuating the pump pistons, so constructed that each pump cylinder and its associated piston may be quickly and 30 easily disconnected independently of the other cylinder and piston.

Still another object of the invention is to 35 provide an apparatus of the class set forth having parts collapsible to reduce the dimensions of the apparatus.

In the drawings:

Figure 1 is a top plan view of the apparatus showing the piston operating means locked against reverse movement at the conclusion of the discharge stroke of one piston and the suction stroke of the other piston;

Fig. 2 a detail view, partly in horizontal section, showing the intake and discharge governing valves and the conduits governed thereby, the valves being in the position shown in Fig. 1;

Fig. 3 a view similar to Fig. 2 showing the valves adjusted for movement of the pump pistons in the opposite direction;

Fig. 4 a transverse section on the line 4—4 of Fig. 1, the valves being adjusted to the positions shown in Figs. 1 and 2;

Fig. 5 a view similar to Fig. 4, the valves being adjusted to the positions shown in Fig. 3;

55

Fig. 6 a side elevation of the apparatus, looking toward the left thereof as shown in Fig. 1;

60

Fig. 7 a top plan view of one of the adjustable carriages;

65

Fig. 8 a transverse section on the line 8—8 of Fig. 6;

Fig. 9 a fragmentary central longitudinal section; and

Figs. 10 and 11 detail views of the pawl and ratchet locking mechanism.

Referring to the various parts by numerals, 1 designates a supporting plate or bed member having depending side flanges or ribs 2 and depending end flanges or ribs 3. Two ribs or flanges 4 extend between the ribs 2 adjacent opposite ends of the plate 1 parallel with the ribs 3, and said ribs 3 and 4 are formed with registering horizontal slots or guide ways 5 and 6, respectively, 75 in which extensible end plates 7 forming extensions of the bed 1 are slidably mounted. Each plate 7 is adapted to be locked in its adjusted position by a suitable clamping screw 8 which extends through the bed plate 80 1 and has a thumb nut 9 threaded on its upper end. Each plate 7 is provided at its outer end with a suitable knob 10 to facilitate adjustment thereof, and is provided at its inner end with a stop screw or projection 11 adapted to engage rib 4 to limit the outward movement of the plate.

Two oppositely facing glass syringe barrels 12, preferably provided with graduations (as shown) to indicate the capacity 90 thereof, are removably supported on two pairs of saddles 13. The saddles are rigidly held to the bed member 1 in any suitable manner and may be cast integrally therewith if desired. Each saddle or upright 95 support 13 is formed with a concave seat or recess 14 in its upper end to receive a syringe barrel, and said saddles are arranged in alignment longitudinally of the member 1, two of the saddles being located at each side 100 of the center of the bed member 1. Solid glass plungers or pistons 15 are mounted in the syringe barrels 12, each of said plungers being formed with a head 16 at its

outer end connected with the main body portion of the plunger by a reduced shank or neck portion 17. Each syringe barrel 12 is provided at its inner end with the usual nozzle 18 to which a metal nipple 19 is frictionally held at one end.

A standard 20, rigidly held to the base plate 1 centrally of said plate, supports a tubular member 21 which extends transversely of the plate 1 midway between the inner ends of the syringe barrels 12. The tubular member 21 is provided with two oppositely extending nipples 22 and 23 midway its ends in alignment with the nipples 19 on the nozzles of the syringe barrels. Nipple 22 is connected with one of the nipples 19 by a short length of flexible rubber tubing 24, and the nipple 23 is connected with the other nipple 19 by a similar flexible tube or conduit 24. The nipple 22 is provided with a passage or conduit 26 which connects with a conduit 27 extending longitudinally through the tubular member 21, and nipple 23 is provided with a passage 28 which is connected with a passage 29 extending longitudinally through member 21.

An intake valve and an outlet or discharge valve are supported at opposite ends of the member 21, said valves being common to both syringes or pumps. The casing 30 of the intake valve has a nipple 31 provided with a passage 32 communicating with the valve chamber, and said casing is formed with a threaded tubular extension 33 provided with two passages 34 and 35 connecting the valve chamber with the adjacent ends of the passages 27 and 29, respectively, in member 21. A plug valve 36 is rotatably mounted in the valve chamber of casing 30 and is provided with a port or passage 37 extending therethrough which is widened or enlarged at one end, as shown, so that said intake valve 36 may be rotated to connect passages 34 and 35 alternately with intake passage 32 through port 37. The valve casing 30 is held to member 21 by a sleeve 38 threaded on extension 33 of the valve casing and having a flange or shoulder adapted to abut against a circumferential flange or shoulder on the end of member 21. Any other suitable form of coupling may be provided if desired. The opposite ends of passages 27 and 29 communicate with passages 39 and 40, respectively, formed in an externally threaded tubular extension 41 on the discharge valve casing 42. This valve casing is connected to member 21 by a threaded sleeve 43, in the same manner as the intake valve. To insure registration of the passages in the extensions of the valve casings with the passages 27 and 29, the member 21 is provided with a socket in each end thereof in which a stud or pin 45 on the end of the extension of the valve casing is adapted 65 to seat, as shown in Fig. 4. The valve cas-

ing 42 is provided with a nipple 46 having a discharge passage 47 therethrough with which passages 27 and 29 may be alternately connected by a port 48 in the discharge valve 49. The plug valve 49 is rotatable in the casing 42 and the port 48 is enlarged at one end, as shown, so as to register with passage 47 when the other end of the port is connected with either of the passages 27 or 29. The extent of rotary movement of the valve 75 plugs 36 and 49 is limited by the usual pin-and-slot device, as shown in Figs. 4 and 5.

Two flexible conduits, such as rubber tubes 50 and 51 are connected to the nipples 31 and 46, respectively, and said tubes are provided with the usual tapered nipples or nozzles 52 at their free ends to which the usual needles 53, which are inserted in the veins of the donor and receiving patient, are frictionally connected in the usual manner.

The opposed plungers 15 are connected by a reciprocable frame, comprising side rods 54 and end bars 55, to cause said plungers to move in unison in the same direction relatively to the base plate to thereby impart a suction stroke to one plunger during the discharge stroke of the other plunger. The syringes are removably held down in the saddles 13 by adjustable and detachable clamps 56 having hook portions engaging over the syringe plungers and engaging against the flanged outer ends of the syringe barrels. Each clamp rests at its lower end on the base plate 1 to prevent rocking of the clamp, and each clamp is provided with an arm 57 having a horizontal slot 58 therein open at one end. A clamping screw 59 extends through slot 58 and is threaded into the adjacent saddle 13. It will be obvious that the clamps may be adjusted longitudinally of the base plate and that they may be readily detached when the clamping screws are loosened.

Two carriages 60, each having a pair of rollers 61 journaled thereon and adapted to roll upon the upper face of the adjacent plate or extension 7 of the base 1, are adjustably held to the reciprocating frame to move therewith. The carriages are slidable along the rods 54 of the frame and may be adjusted toward and from the end bars 55 by means of screws 62. Screws 62 are threaded through the carriages and are rotatably supported in the end bars 55, being held against endwise movement relatively to the end bars by screws 63 which engage in circumferential grooves 64 in the screws 62, as shown in Fig. 9. The plungers 15 are removably connected at their outer ends with the carriages 60 to move in unison with the frame and carriages and to permit adjustment of the plungers relatively to each other and to the pump barrels by adjusting the carriages along the frame. Each carriage is provided with a fixed upwardly ex-

tending plate 65 adapted to bear against the outer end of the plunger head 16, and with an upwardly extending forked plate or yoke 66 adapted to embrace the neck 17 of the plunger and bear against the inner end of the plunger head 16. The plunger is thus held to the carriage to move back and forth therewith, but may be readily disconnected from the carriage, when clamp 56 is removed, by lifting the syringe upwardly. The plate or yoke 66 is provided with a horizontal flange 67 provided with elongated slots through which screws 68 extend for adjustably holding the yoke to the carriage.

In order to prevent reversal of the direction of movement of the plunger-connecting frame without first reversing the adjustment of the intake and discharge valves, means is provided for automatically locking the frame against reversal until the valves are properly adjusted. For this purpose the stems or handles 69 of the two plug valves are connected with a substantially U-shaped link or operating yoke 71 by pivot screws 70. The lower transverse member of link 71 extends under one of the tubes 24 and above the side rods 54 of the plunger-connecting frame. A gravity pawl 72, having rounded ends, is suspended from the transverse member of link 71 centrally of said member and is held against rotation by the walls of a vertical slot in a boss 73 formed on the under side of the link. When the yoke is shifted to adjust the valves to the position shown in Fig. 2, the pawl rests on one of the rods 54, and when the valves are adjusted, as shown in Fig. 3, the pawl rests on the opposite rod 54. The rounded ends of the pawl permit the pawl to ride up on the rods when shifted endwise. The rods 54 are provided with sets of oppositely facing ratchet teeth 74 and 75 with which the gravity pawl 72 is adapted to engage so as to permit movement of the frame in one direction only when the pawl overlies either bar. It will thus be observed that after the frame is shifted in one direction, movement thereof and of the pump plungers cannot be reversed without shifting the link 71 to reverse the adjustment of the valves.

All of the parts except the rubber tubes and the syringe plungers and barrels are preferably made of metal and nickel-plated. While I prefer to employ ordinary glass syringes as pumps, it will be obvious that other forms of pumps may be employed.

With the mechanism above described it will be seen that a continuous flow of blood from the donor to the receiving patient may be obtained and that accidental back-flow of the blood is impossible. It will also be observed that the length of the apparatus may be reduced by sliding plates 7 inwardly, this being advantageous in packing the appara-

tus for shipment and also permitting sterilization of the apparatus in a tank of minimum size.

The apparatus may be used for other purposes besides the transfusion of blood, such as aspirating or pumping various fluids or pus from cavities or passages in the body.

What I claim is:

1. An apparatus of the class set forth comprising a support, a pair of syringes mounted on the support, means connecting the plungers of said syringes for simultaneous movement in opposite directions relatively to the syringe barrels, a member mounted on the support having two passages therethrough, means connecting each of said passages intermediate its ends with one syringe barrel, a pair of valve casings held to said member, and a pair of valve plugs rotatable in said valve casings each having a passage therethrough adapted to connect either of the passages through the member with a single passage through its valve casing. 75 80

2. An apparatus of the class set forth comprising a support, a pair of syringes mounted on the support, means connecting the plungers of said syringes for simultaneous movement in opposite directions relatively to the syringe barrels, a member mounted on the support having two passages therethrough, means connecting each of said passages intermediate its ends with one syringe barrel, a pair of valve casings held to said member, a pair of valve plugs 90 95 rotatable in said valve casings each having a passage therethrough adapted to connect either of the passages through the member with a single passage through its valve casing, and means for simultaneously rotating the valve plugs to place the passage through one plug in communication with one passage through the member and the passage through the other plug in communication with the other passage through the member. 100 105 110

3. In an apparatus of the class set forth, the combination of a pair of syringes, means connecting the plungers of said syringes to cause one of said plungers to move on its suction stroke while the other plunger moves on its ejecting stroke, an intake valve casing having an intake port, an outlet valve casing having an outlet port, means forming independent conduits each of which is in communication with the barrel of one syringe 115 120 and both valve casings, valves in said casings, and means for operating said valves in unison to simultaneously connect one of said conduits with the intake port in the intake valve casing and the other conduit with the outlet port in the outlet valve casing. 125

4. In an apparatus of the class set forth, the combination of a pair of syringes, means connecting the plungers of said syringes to cause one of said plungers to move on its 130

suction stroke while the other plunger moves on its ejecting stroke, an intake valve casing having an intake port, an outlet valve casing having an outlet port, means forming independent conduits each of which is in communication with the barrel of one syringe and both valve casings, valves in said casings, means for operating said valves in unison to simultaneously connect one of said conduits with the intake port in the intake valve casing and the other conduit with the outlet port in the outlet valve casing, and means for automatically locking the syringe plungers against reverse movement at the end of each stroke thereof.

5. In an apparatus of the class set forth, the combination of a pair of syringes, means connecting the plungers of said syringes to cause one of said plungers to move on its suction stroke while the other plunger moves on its ejecting stroke, an intake valve casing having an intake port, an outlet valve casing having an outlet port, means forming independent conduits each of which is in communication with the barrel of one syringe and both valve casings, valves in said casings, means for operating said valves in unison to simultaneously connect one of said conduits with the intake port in the intake valve casing and the other conduit with the outlet port in the outlet valve casing, and coöperating means movable with the plunger-connecting means and valve-operating means for locking the plungers against reverse movement until the valve-operating means is operated to reverse the positions of the valves.

6. In an apparatus of the class set forth, the combination of a pair of syringes, means connecting the plungers of said syringes to cause one of said plungers to move on its suction stroke while the other plunger moves on its ejecting stroke, an intake valve casing having an intake port, an outlet valve casing having an outlet port, means forming independent conduits each of which is in communication with the barrel of one syringe and both valve casings, valves in said casings, means for operating said valves in unison to simultaneously connect one of said conduits with the intake port in the intake valve casing and the other conduit with the outlet port in the outlet valve casing, and a pawl movable with the valve-operating means into coöperative relation with first one and then the other of two series of oppositely facing ratchet teeth on the plunger-connecting means.

7. In an apparatus of the class set forth, the combination of a support, two syringe-barrel cradles mounted on said support, a pair of oppositely facing syringe barrels mounted in said cradles, a pair of oppositely facing plungers reciprocal in said

barrels, a frame slidably supported by said cradles to move longitudinally of the syringe barrels, means connecting the plungers with said sliding frame, and means mounted on the support for connecting each syringe barrel with an intake conduit during the suction stroke of the plunger therein and with a discharge conduit during the ejecting stroke of the plunger.

8. In an apparatus of the class set forth, the combination of a support, two syringe-barrel cradles mounted on said support, a pair of oppositely facing syringe barrels mounted in said cradles, a pair of oppositely facing plungers reciprocal in said barrels, a frame slidably supported by said cradles to move longitudinally of the syringe barrels, means connecting the plungers with said sliding frame, means on the support formed with an intake opening and a discharge opening and two independent conduits each of which is in communication with both of said openings, means connecting each syringe barrel with one of said conduits, a valve operable to alternately close communication between said conduits and the intake opening, and a valve operable to alternately close communication between said conduits and said discharge opening.

9. In an apparatus of the class set forth, the combination of a support, two syringe-barrel cradles mounted on said support, a pair of oppositely facing syringe barrels mounted in said cradles, a pair of oppositely facing plungers reciprocal in said barrels, a frame slidably supported by said cradles to move longitudinally of the syringe barrels, means connecting the plungers with said sliding frame, a flexible intake conduit, a flexible discharge conduit, means on the support forming connections between each syringe barrel and both of said conduits, and valve means for closing communication between the intake conduit and the syringe barrels during the ejection strokes of the plungers and between the discharge conduit and said barrels during the suction strokes of the plungers.

10. In an apparatus of the class set forth, the combination of a support, a pair of oppositely facing syringe barrels mounted on the support, plungers reciprocal in said barrels, a frame slidably mounted on the support to move longitudinally of the syringe barrels, devices movable with the frame for connecting the plungers with the frame to slide therewith, means for adjusting said plunger-connecting devices independently longitudinally of the frame, and means for connecting the syringe barrels with the veins of the donor and receiver of blood.

11. In an apparatus of the class set forth, the combination of a support, a pair of op-

positely facing pump barrels mounted on the support, plungers reciprocable in said barrels, a frame shiftable longitudinally of the pump barrels, a pair of roller carriages connected with said frame to move therewith on said support, means for adjusting said carriages longitudinally of the frame, means carried by each of said carriages for connecting one of said plungers therewith, 10 and means for connecting the pump barrels with the arteries of the donor and receiver of blood.

12. In an apparatus of the class set forth, the combination of a support, a pair of oppositely facing pump barrels mounted on the support, plungers reciprocable in said barrels, a frame shiftable longitudinally of the pump barrels, a pair of roller carriages connected with said frame to move there- 15 with on said support, means for adjusting said carriages longitudinally of the frame, means carried by each of said carriages for connecting one of said plungers therewith, and a pair of clamping members adjustably 20 and detachably held to the support for holding the pump barrels to the support.

13. In an apparatus of the class set forth, the combination of a support, cradles mounted on the support, a pair of pumps resting 30 in said cradles having reciprocating pistons, means for removably holding the pumps in said cradles, an intake valve and an outlet valve common to both pumps, reciprocable means connecting the pump pi- 35 tons operable to cause one piston to make a suction stroke while the other piston makes an ejecting stroke, and means for simultaneously operating said valves.

14. In an apparatus of the class set forth, the combination of a support, cradles mounted on the support, a pair of pumps resting 40 in said cradles having reciprocating pistons, means for removably holding the pumps in said cradles, an intake valve and an outlet valve common to both pumps, reciprocable 45 means connecting the pump pistons operable to cause one piston to make a suction stroke while the other piston makes an ejecting stroke, reciprocable means connecting said valves shiftable transversely of the 50 pump-piston operating means for simultaneously operating the valves, and coöperating means carried by the piston-operating means and valve-operating means for locking the piston-operating means against reverse movement at each limit of its reciprocating movement.

15. In an apparatus of the class set forth, the combination of a support having extensible end portions, cradles on said support, a 60 pair of opposed pumps supported in said cradles having reciprocating pistons, a pair of valves common to both pumps for governing the flow of liquid to and from the pumps, means connecting said valves for 65 simultaneous operation, a frame slidably guided in said cradles for actuating the pump pistons, roller carriages connected with said frame and traveling on the extensible end portions of the support, and 70 means on said carriages for connecting the pump pistons therewith.

In testimony whereof I hereunto affix my signature.

MARTIN LEWIS JANES.
